US00D545217S

(12) **United States Design Patent** (10) **Patent No.:** **US D545,217 S**
Jeric et al. (45) **Date of Patent:** **** Jun. 26, 2007**

(54) **FLEXIBLE PACKAGE**

(75) Inventors: **Laura A. Jeric**, Chicago, IL (US);
Kelly Arnold, Chicago, IL (US);
Kenneth Pokusa, Indian Head Park, IL (US); **Panagoitis Kinigakis**, Roscoe, IL (US); **Trisha A. Wood**, Rupert, ID (US)

(73) Assignee: **Kraft Foods Holdings, Inc.**, Northfield, IL (US)

(**) Term: **14 Years**

(21) Appl. No.: **29/229,136**

(22) Filed: **May 3, 2005**

(51) **LOC (8) Cl.** **09-05**

(52) **U.S. Cl.** **D9/709**

(58) **Field of Classification Search** **D9/702-705, D9/707-710; 206/439, 459.1; 24/415, 339, 24/400, 585.12; 493/213; 229/80; 383/5, 383/61.2, 61.3, 203, 204, 62, 63, 64**

CLAIM

The ornamental design for a flexible package, as shown and described.

DESCRIPTION

FIG. 1 is a perspective view of a flexible package showing a first embodiment of our new design drawn broken away to show indeterminate length.

FIG. 2 is a front elevation view of the flexible package of FIG. 1;

FIG. 3 is a rear elevation view of the flexible package of FIG. 1;

FIG. 4 is an elevation view of one side of the flexible package of FIG. 1;

FIG. 5 is an elevation view of the other side of the flexible package of FIG. 1;

FIG. 6 is a top plan view of the flexible package of FIG. 1; FIG. 7 is a bottom plan view of the flexible package of FIG. 1;

FIG. 8 is a perspective view of the flexible package of FIG. 1 with contents therein;

FIG. 9 is a front elevation view of the flexible package of FIG. 8;

FIG. 10 is a rear elevation view of the flexible package of FIG. 8;

FIG. 11 is an elevation view of one side of the flexible package of FIG. 8;

FIG. 12 is an elevation view of the other side of the flexible package of FIG. 8;

FIG. 13 is a top plan view of the flexible package of FIG. 8; and

FIG. 14 is a bottom plan view of the flexible package of FIG. 8.

FIG. 15 is a perspective view of a flexible package showing a second embodiment of our new design drawn broken away to show indeterminate length.

FIG. 16 is a front elevation view of the flexible package of FIG. 15;

FIG. 17 is a rear elevation view of the flexible package of FIG. 15;

FIG. 18 is an elevation view of one side of the flexible package of FIG. 15;

FIG. 19 is an elevation view of the other side of the flexible package of FIG. 15;

FIG. 20 is a top plan view of the flexible package of FIG. 15; FIG. 21 is a bottom plan view of the flexible package of FIG. 15;

FIG. 22 is a perspective view of the flexible package of FIG. 15 with contents therein;

FIG. 23 is a front elevation view of the flexible package of FIG. 22;

FIG. 24 is a rear elevation view of the flexible package of FIG. 22;

FIG. 25 is an elevation view of one side of the flexible package of FIG. 22;

FIG. 26 is an elevation view of the other side of the flexible package of FIG. 22;

FIG. 27 is a top plan view of the flexible package of FIG. 22; and

FIG. 28 is a bottom plan view of the flexible package of FIG. 22.

FIG. 29 is a perspective view of a flexible package showing a third embodiment of our new design drawn broken away to show indeterminate length.

FIG. 30 is a front elevation view of the flexible package of FIG. 29;

FIG. 31 is a rear elevation view of the flexible package of FIG. 29;

FIG. 32 is an elevation view of one side of the flexible package of FIG. 29;

FIG. 33 is an elevation view of the other side of the flexible package of FIG. 29;

FIG. 34 is a top plan view of the flexible package of FIG. 29; FIG. 35 is a bottom plan view of the flexible package of FIG. 29;

FIG. 36 is a perspective view of the flexible package of FIG. 29 with contents therein;

FIG. 37 is a front elevation view of the flexible package of FIG. 36;

FIG. 38 is a rear elevation view of the flexible package of FIG. 36;

FIG. 39 is an elevation view of one side of the flexible package of FIG. 36;

FIG. 40 is an elevation view of the other side of the flexible package of FIG. 36;

FIG. 41 is a top plan view of the flexible package of FIG. 36; and,

FIG. 42 is a bottom plan view of the flexible package of FIG. 36.
